TREATMENT OF HYDROCARBON OILS

Jean Delattre Seguy, Chicago, Ill., assignor to
 Universal Oil Products Company, Chicago, Ill.,
 a corporation of Delaware

Application December 12, 1938, Serial No. 245,152

7 Claims. (Cl. 196—50)

This invention relates to processes applicable to the treatment of crude petroleums which contain appreciable proportions of gasoline, intermediate fractions and heavy non-volatile residua.

It is more specifically concerned with a method of operation involving a combination of inter-related steps aimed at the ultimate production of optimum yields of high octane number gasoline and specification fuel oil or coke. The various steps involve a primary non-cracking distillation to produce an overhead cut, a number of intermediate cuts and a residuum, each fraction thereafter being treated either pyrolytically or catalytically according to its chemical and physical properties to produce a maximum yield of the desired high antiknock gasoline and specification fuel oil or coke.

In one specific embodiment the present invention comprises fractionating crude petroleum to produce an overhead gasoline, light and heavy intermediate fractions and residuum, thermally reforming said light intermediate fraction, catalytically cracking the heavy intermediate fraction, commingling the residual liquids produced in each of the above operations and thermally cracking the same to produce additional yields of gasoline and either specification fuel oil or coke, while producing gasoline of at least 70 octane number at all points.

The attached diagrammatic drawings show by the use of conventional figures in general side elevation and without reference to any particular absolute or relative scale, an arrangement of interconnected units in which the process may be conducted.

Referring to the drawing, line 1 containing valve 2 indicates a charge line for the admission of crude oil to fractionator 3. In this primary step of the process the incoming material is heated by conventional means not shown to a temperature and under a pressure sufficient to effect a primary rough fractionation. The pressure used may vary from atmospheric to approximately 100 pounds per square inch and the temperature will vary from approximately 500 to 750° F. The type and character of the fractionating column may be varied to suit the needs of any particular crude oil since all of these materials vary widely with respect to their boiling characteristics and content of overhead gasoline, intermediate fractions and residual constituents.

In the drawing, overhead vapor line 4 containing valve 5 preferably leads the vapors of the natural gasoline content of the crude oil to

condensing and cooling equipment not shown. In accordance with the invention, the primary fractionating column is operated so that the overhead gasoline has an octane number of at least 70 when tested by the Motor method. This will obviously vary the end-point of this fraction since naphthenic base crudes will permit the use of end-points of 400° F. or higher in each fraction while in the case of highly paraffinic crudes, such as those from Pennsylvania or Michigan, this end-point will need to be reduced materially if 70 octane number product is to be obtained.

Fractions of crude oil, comprising the relatively heavy ends of gasoline and the illuminating oil distillates, are preferably taken as a side cut from fractionating column 3 through line 6 containing valve 7 and directed to a pyrolytic reforming unit by pump 8 which discharges 15 through line 9 containing valve 10 and leading to line 11 and thence to heating element 12 arranged in furnace 13. The reforming unit is preferably operated at pressures within the range of 500 to 1000 pounds or more per square 20 inch and coil outlet temperature of 1000 to 1100° F., the heated products pass through line 14 containing valve 15 to a reaction chamber 16 provided to permit additional time for the completion of the desired reactions, the total cracked 25 products then passing through line 17 containing valve 18 to a separator 19 which operates at a reduced pressure of the order of 50 to 100 pounds per square inch and wherein vapors separate 30 from residual liquid. The latter is withdrawn 35 from the separator through line 20 and valve 21 for further treatment as will be subsequently described.

The vaporous conversion products pass through line 22 containing valve 23 to fractionator 24 40 wherein gasoline boiling range material is separated from heavier products, the latter being condensed as reflux condensate. The reflux condensate may be withdrawn from the lower portion of the fractionator through line 25 containing valve 26 to pump 27 by means of which it 45 may be returned through line 28 containing valve 29 to line 11 and thence to coil 12 for further conversion. When it is not desired to return the reflux condensate to the heating coil, it may be commingled with the residual liquid withdrawn from separator 19 through line 20 by well known means not illustrated, or may be utilized 50 as a cooling medium for the hot conversion products discharged from the heating coil. Fractionated vapors of the desired end-boiling point

and fixed gases are withdrawn from the upper portion of fractionator 24 through line 25' containing valve 26' and passed to condenser 21', from which condensed liquids and uncondensed gases follow line 28' containing valve 29' to receiver 30 having a fixed gas release line 31 containing valve 32 and a gasoline draw line 33 containing valve 34. This unit is preferably operated in conformity with the general subject of the invention so that gasoline of at least 70 octane number is produced. The gas mixture evolved through line 31 may be subjected to polymerization processes to produce gasoline boiling range polymers and augment the yield and quality of the total gasoline produced in the process.

As an alternative method of operation, included within the scope of this invention, separator 19 may be operated to effect a fairly accurate separation of gasoline boiling range material and residual products. The gasoline boiling range material may then be withdrawn through line 22 into fractionator 24, which would preferably operate as a stabilizing column, the final gasoline product being withdrawn from the lower portion thereof and fixed gases being withdrawn from the upper portion thereof.

Devices such as temperature regulating means between separator 19 and fractionator 24, the refluxing system for controlling the overhead from fractionator 24 and other incidental controls and methods of cooling are omitted from the drawing in the interests of simplicity.

Heavier intermediate fractions of the crude oil charge are withdrawn from fractionator 3 by way of line 35 containing valve 36 to pump 37 and discharged through line 38 containing valve 39 through line 40 to heating coil 41. Heating element 41 is arranged in a suitable furnace 42, whereby the products passing therethrough may preferably be heated to some temperature within the approximate range 900 to 1050° F. depending upon the boiling range and refractory properties of the material supplied thereto. The heated products are passed through line 43 containing valve 44 to catalytic reaction chamber 45. The pressure in this unit is preferably only slightly superatmospheric since best results are usually obtained when granular catalysts are employed if the formation of hydrogen is not depressed by superimposed pressure and dehydrogenation reactions occur to increase the degree of unsaturation and hence the antiknock value of the final product.

A number of catalysts may be used in the reaction chamber of this unit, the selection of any one depending upon numerous circumstances, such as the nature of the oil entering the unit and the availability and cost of the catalyst. The invention is not limited to the use of any particular catalyst, but some may be mentioned as being particularly efficient such as, for example, composite catalysts consisting of mixtures of silica and alumina in varying proportions and produced by co-precipitation, successive precipitation or wet mixing of hydrated silica and hydrated alumina followed by exhaustive washing to remove occluded salts, calcining at moderate temperatures and sizing or pelleting to produce catalytic particles of a practical diameter. In some instances good results may be obtained by utilizing granular catalysts consisting of relatively inert and generally siliceous supports having deposited on their surfaces and in their pores varying amounts of metal, metal oxides and some 75 products, while the uncondensed vapors are

metal salts. Obviously, none of the materials will be exactly equivalent in their effects on the same or different charging stocks, and their selection is in any case a matter of expediency.

5 The total products from the catalytic reaction chamber pass through line 46 containing valve 47 into separator 48, wherefrom residual material is withdrawn through line 49 containing valve 50 for further treatment as will be subsequently described. Vaporous conversion products from separator 48 are passed through line 51 containing valve 52 into fractionator 53. This fractionator is again preferably operated to produce a gasoline boiling range material of at least 70 octane number, the vapors and fixed gases following line 54 containing valve 55 to condenser 56, from which the condensed liquids and uncondensed gases pass through line 57 containing valve 58 to receiver 59. The gas withdrawn at 10 this point in the system through line 60 containing valve 61 may also be treated for the utilization of its olefin content in admixture with gases withdrawn from line 31, as previously mentioned. The gasoline products from the catalytic unit is 15 withdrawn through line 62 containing valve 63 and blended with the gasoline produced at other points in the process.

Intermediate boiling range fractions from catalytic cracking are withdrawn from fractionator 53 through line 64 containing valve 65 to pump 66 by means of which they may be returned through line 67 containing valve 68 to line 40 and thence to heating coil 41 for further conversion. When it is not desired to return the intermediate fractions withdrawn from the lower portion of fractionator 53 to heating coil 41 for further conversion, it is within the scope of the invention to commingle all or a portion of this material with the residual liquid withdrawn from separator 48 through line 49, by well known means not shown, for further treatment as will be presently described.

In accordance with the invention the heavier fractions of the crude oil withdrawn from the lower portion of fractionator 3 through line 69 containing valve 70 are commingled with the residual liquid from the reforming operation withdrawn from separator 19 through line 20 and with the residual liquid from the catalytic cracking operation withdrawn from separator 48 through line 49. In a copending application I have disclosed a process whereby a similar residual mixture may be flash distilled to produce specification fuel oil. With certain crude oils it 45 would not be possible to produce specification fuel oil by flash distillation or stripping and I, therefore, subject this residual mixture to thermal cracking to produce either specification fuel oil or coke, while at the same time producing additional yields of gasoline of at least 70 octane number.

60 Referring to the drawings, the commingled residual liquids are supplied to pump 71, by means of which they are fed through line 72 containing valve 73 and line 74 to heating coil 75 disposed to receive heat from furnace 76.

Conditions employed in the thermal cracking unit are mild and of the order of 900° F. and 400 pounds per square inch. The heated products 65 from heating element 75 pass through line 76' containing valve 77 to reaction chamber 78. The total cracked products pass through line 79 containing valve 80 to a reduced pressure separator 81 which functions to remove heavy residual products, while the uncondensed vapors are

passed through line 82 containing valve 83 to fractionator 84. Fractionator 84 functions to produce an overhead gasoline of the required boiling range and antiknock value, the vapors of this gasoline plus incondensable gases pass through line 85 containing valve 86 and to condenser 87, from which condensed liquids and uncondensed gases follow line 88 containing valve 89 to receiver 90 having a fixed gas release line 91 containing valve 92 and a gasoline draw line 93 containing valve 94.

As already specified at other points, the gas mixture released from this receiver may be treated to polymerize their olefinic content by any method either thermal or catalytic and the gasoline withdrawn should have at least 70 octane number. Intermediate reflux condensate from fractionator 84 passes through line 95 containing valve 96 to recycle pump 97 by means of which it is fed through line 98 containing valve 99 and line 74 to heating coil 75 for further conversion.

The residual materials from separator 81, which preferably operates at a pressure of the order of 50 to 100 pounds per square inch, pass through line 100 and, if of proper characteristics, may be withdrawn through line 101 containing valve 102 as specification fuel oil or, if unsatisfactory as specification fuel oil, may be supplied through line 103 containing valve 104 to flash or coke chamber 105. Chamber 105 may be operated to produce either specification fuel oil or coke. Any well known means for stripping the residual liquid therein to specification fuel oil such as steam, gases, closed heating coils, etc., may be employed.

When producing coke in chamber 105 any means may be employed to effect the coking of this residual material such as, for example, independently heating the residual liquid in a separate heating coil, the use of highly heated vapors or gases as a heat carrying medium, etc., may be employed. Drain line 106 containing valve 107 may be used for withdrawing specification fuel oil from this chamber or may be used for the introduction of steam, heat carrying medium or other materials when processing to coke. Vapors from chamber 105 pass through line 108 containing valve 109 to fractionator 110, which typifies any arrangement which will permit the production of a gas fraction containing all constituents not needed to give the required vapor pressure to the gasoline, these gases being withdrawn through line 111 containing valve 112, and a gasoline fraction which is withdrawn through line 113 containing valve 114 and which preferably has the properties of at least 70 octane number as already specified. Heavy intermediate fractions may be withdrawn from fractionator 110 through line 115 containing valve 116 to pump 117 by means of which it may be returned through line 118 containing valve 119 to chamber 105. When these heavy intermediate fractions are suitable as cracking stock, it is within the scope of the invention to supply the same to the thermal cracking zone for additional conversion therein.

The foregoing description is a general outline of the invention and the following example is given to show the character of the results obtainable in its practicable operation, although none of the data is introduced with the object of unduly limiting the broad scope of the invention.

Crude oil was fractionated into four cuts as follows:

- (1) 25% of 350° F. end-point gasoline having an octane number of 70;
- (2) 20% of the naphtha fraction;
- (3) 30% of a gas oil fraction;
- (4) 25% of a residuum.

The naphtha fraction was reformed at a temperature of 1000° F. and a pressure of 500 pounds per square inch, while the gas oil fraction was catalytically cracked in the presence of a granular catalyst comprising silica supporting about 10% of alumina, utilizing a temperature of 950° F. and a pressure of 10 pounds per square inch. The residual liquid from all three operations was thermally cracked at a temperature of about 930° F. and a pressure of 350 pounds per square inch.

When processing to specification fuel oil the following overall yields by volume may be obtained:

	Percent
(1) 72 octane number gasoline	73
(2) Navy specification fuel oil	17
(3) Gas and loss	10

When processing to coke the following overall yields by volume may be obtained:

	Percent
(1) 72 octane number gasoline	76
(2) Coke, gas and loss	24

The above yields include the gasoline produced by polymerizing 3 and 4 carbon atom olefins in the gases in contact with a solid phosphoric acid catalyst.

I claim as my invention:

1. A process for treating crude petroleum which comprises fractionating crude petroleum to produce overhead gasoline, light and heavy intermediate fractions, and residuum, cooling, condensing and collecting said overhead gasoline, thermally reforming said light intermediate fractions, catalytically cracking said heavy intermediate fractions, and thermally cracking said residuum together with residual liquids produced in the reforming and catalytic cracking operations to produce specification fuel oil.

2. A process for treating crude petroleum which comprises fractionating said petroleum to produce overhead gasoline of at least 70 octane number, light and heavy intermediate fractions and residuum, cooling, condensing and collecting said overhead gasoline, thermally reforming said light intermediate fractions to produce gasoline of at least 70 octane number, catalytically cracking said heavy intermediate fractions to produce gasoline of at least 70 octane number, and thermally cracking said residuum along with residual liquids produced in the reforming and catalytic cracking operations to produce specification fuel oil.

3. A process for treating crude petroleum which comprises fractionating said petroleum to produce overhead gasoline of at least 70 octane number, light and heavy intermediate fractions and residuum, cooling, condensing and collecting said overhead gasoline, thermally reforming said light intermediate fractions to produce gasoline of at least 70 octane number, catalytically cracking said heavy intermediate fractions to produce gasoline of at least 70 octane number, and thermally cracking said residuum along with residual liquids produced in the reforming and catalytic cracking operations to produce specification fuel oil and gasoline of at least 70 octane number.

4. A process for treating crude petroleum which comprises fractionating crude petroleum to produce overhead gasoline, light and heavy intermediate fractions, and residuum, cooling, condensing and collecting said overhead gasoline, thermally reforming said light intermediate fractions, catalytically cracking said heavy intermediate fractions and fractionating resultant vaporous products independently of said crude petroleum, and thermally cracking said residuum together with residual liquids produced in the reforming and catalytic cracking operations to produce coke.

5. A process for treating crude petroleum which comprises fractionating said petroleum to produce overhead gasoline of at least 70 octane number, light and heavy intermediate fractions and residuum, cooling, condensing and collecting said overhead gasoline, thermally reforming said light intermediate fractions to produce gasoline of at least 70 octane number, catalytically cracking said heavy intermediate fractions to produce gasoline of at least 70 octane number and fractionating resultant vaporous products independently of said crude petroleum, and thermally cracking said residuum along with residual liquids produced in the reforming and catalytic cracking operations to produce coke.

6. A process for treating crude petroleum which comprises fractionating said petroleum 30

to produce overhead gasoline of at least 70 octane number, light and heavy intermediate fractions and residuum, cooling, condensing and collecting said overhead gasoline, thermally reforming said light intermediate fractions to produce gasoline of at least 70 octane number, catalytically cracking said heavy intermediate fractions to produce gasoline of at least 70 octane number and fractionating resultant vaporous products independently of said crude petroleum, and thermally cracking said residuum along with residual liquids produced in the reforming and catalytic cracking operations to produce coke and gasoline of at least 70 octane number.

7. A conversion process which comprises fractionating crude petroleum under substantially non-cracking conditions to form a light fraction containing low anti-knock gasoline components, an intermediate fraction consisting essentially of hydrocarbons heavier than gasoline, and topped crude, thermally reforming said light fraction, catalytically cracking said intermediate fraction and fractionating resultant vaporous products independently of said crude petroleum, combining the topped crude with residual products of the thermal reforming and the catalytic cracking, and thermally cracking the resultant mixture.

JEAN DELATTRE SEGUY.
